UNITED STATES PATENT OFFICE.

FREDERICK WILLIAM VICKERY, OF LONDON, ENGLAND.

PAPER PILING OR LAYING MACHINE.

1,144,269.

Specification of Letters Patent. Patented June 22, 1915.

Application filed December 8, 1913. Serial No. 805,420.

To all whom it may concern:

Be it known that I, FREDERICK WILLIAM VICKERY, a subject of the King of Great Britain, residing at London, England, have 5 invented certain new and useful Improvements in or Connected with Paper Piling or Laying Machines, of which the following is a specification.

The object of this invention is to position 10 the pressers of paper piling or laying machines next to the side gages, in order to press the sheets down into the boxes or equivalents, and on to the pile, and thus enable the sheets to be kept straight with their 15 edges properly positioned between said gages, and in order, also, to actuate any suitable mechanism for regulating the raising and lowering of the delivery mechanism and its associated parts or the table or its 20 equivalent.

The actuating mechanism just referred to does not require timing relative to the entrance of the sheet and this avoids the adjustment necessary in the ordinary machine 25 in which consideration must be paid to the varying thicknesses of the paper being fed.

I will explain my invention as used in connection with my British prior Patents Nos. 17257/06, 21485/10, and 12143/11, although 30 it is understood that I do not restrict myself to the particular actuating mechanism shown and described in those patents, nor to the construction shown and described in the present case, which is only an example of 35 carrying my invention into practical effect for one particular use, and which will require to be modified without departing from the spirit of the invention when applied to various uses.

40 According to the present invention, vertically sliding presser members are provided at each side of the side gages shown in my said patents, and such members may be plain or have ratchet shaped teeth or grooves to 45 engage the edges of the sheets upon being lowered to press the sheets into the boxes. These members are raised by positive action and are allowed to lower by gravity, which method enables the lowering movement to be 50 arrested as soon as the bottom of the member comes in contact with the top of the pile; the thickness of the said members is such as not to interfere with the passage of the sheet on to the pile, so that it is possible to move them 55 up while the sheet is passing on to the pile until the end has passed clear of the wedges

shown in said patents, when the next downward movement of the members forces the sheet on to the pile and has a tendency to flatten the pile, and as the distance the members travel on their downward stroke regulates the raising and lowering mechanism, as hereafter described, it is an advantage to insure the piles being flat. One or more members may be provided on each side of 60 the side gage shown in British Patent No. 21485/10, and of course, any number of sets of members, according to the number of side gages being employed in the machine. The said members are preferably attached to 65 the side gages so that when these side gages are moved, the members themselves are also moved at the same time, and are thus always kept in the same position relative to the side gages. 75

The invention is illustrated in the accompanying drawing.

Figure 1 is a side elevation of the machine showing the relative positions of the automatic mechanism, the presser appliance, 80 the gage, and a pile of paper. Fig. 2 is a side elevation of one of the side gages, the presser appliance and its carrier. Fig. 3 is an end view of the pressers and gage. Fig. 4 is a fragmental plan view of the automatic 85 mechanism here employed. Fig. 5 is an enlarged view of a detail.

1, 1, are the pressers connected to arms 2, 2, suspended from one end of an arm 3, the other end of which is bent and pivoted to a 90 stud 4 on the frame 5 which carries the side gage 6 and wedge or tapered block 7.

The outer sides of the pressers are formed with inclined, horizontal teeth 8, see Fig. 3, which extend the entire length thereof, 95 and such pressers, when two are employed, are held at a distance apart so that they move simultaneously up and down the opposite sides of the gage plate 6, as it must be understood that when a number of cut sheets 100 are being delivered side by side between the gages, pressers constructed in this way are employed with each gage except the outside gages, in which case there need be only one presser for each, such presser moving up 105 and down on the side of the gage next to the paper.

In Figs. 1 and 2, a gage of special construction is shown as utilized for guiding the pressers 1, which are distanced also by blocks 110 8^a, but such construction forms no part of the present invention.

9 indicates a threaded rod, up and down which the conveyer belt roller, the automatic raising and lowering gear, pressers, gages, their carrier, and other appliances, 5 are moved, as hereafter explained, all of these elements being carried by a frame 10 which is slidably mounted on said rod, (one of such rods being on each side of the machine as will be understood).

10 In the frame 10 is journaled a shaft 11 which extends completely across the machine, and on this shaft there is provided for each rod 9, a worm 12 gearing into a toothed wheel 13, the latter revolving in a bracket 13^a on said frame and having a screw threaded axial opening embracing the screw thread of the rod 9 for effecting the raising and lowering of the frame and the parts carried thereby.

20 In each frame 10 is journaled a rock shaft 14, which, like the shaft 11, extends completely across the machine, and on this rock shaft are fixed levers 15 and 15^a located on opposite sides of the frame, the inner levers 15^a carrying a rod 15^b which also extends across the machine and which is connected to the arms 3 by links 16 on the end of the levers 15^a. The lever 15 on the outside of the frame carries a roller 17 riding over a cam 18 projecting from a wheel 19 loosely mounted on the shaft 11.

30 On the shaft 11 is fixed one toothed member 20 of a clutch, while the other toothed member 21 of the clutch is fixed to one face of the wheel 19, and on said face is also positioned a projecting cam piece 22, the other face of the wheel 19 having a projection 23 formed with a cam shaped edge 23^a. On the face of the projection 23 is another projection 24 extending only over a portion of the projection 23 and having inclined ends 24^a.

40 Secured to the frame is a socket 25 having an extension 25^a which projects into the path of the cam 22, and such socket carries a rod 26, one end 27 of which is provided with a roller 28 which rides on the cam 23^a.

50 A spring 29 connected to the socket 25 and rod 26 normally tends to keep the roller 28 on the cam 23^a, and the rod 26 is provided at the end opposite to the roller 28 with a notch 30 into which the nose 31 of a rocking lever 32 pivoted to the lug 33 on the frames 10 and 5 engages, as hereinafter explained.

55 34 is a spring connected to the frame 10 and the rocking lever 32 to normally hold the nose 31 against a bar 35, which extends across the machine, and which, together with the shaft 11, when the latter is engaged by the jaw 36 of the frame 5, will carry the said frame 5 and its appurtenances.

60 37 are guides on the gage carrier rod 38 to insure a truly vertical movement of the arm 3.

65 One end of the rocking lever 32 is pro-

vided with a roller 39 against which the arm 3 acts.

40 is a gear wheel on the shaft of the belt conveyer roller 41, such wheel 40 meshing with a gear wheel 41^a whose shaft is mounted in the frame 10 and has secured to it a smaller wheel 42 meshing with the wheel 19, so that the conveyer belt will transfer its motion, when required, to the shaft 11 and wheel 13, as hereinafter explained.

75 43 is the usual conveyer belt and 44 the roller for delivering the sheets of paper on to the pile 45.

80 In action, each sheet is passed from the conveyer belt 43 over the wedges 7 where it is curled in a manner well known and passed by the roller 44 on to the pile 45. The motion of the wheel 40 on the shaft of the conveying roller 41, which is driven from any desired part of the machine, is conveyed by the wheels 41^a, 42, to the wheel 19, the cam 18 of which acts upon the levers 15 and 15^a and moves the arm 3 and pressers 1 upward to a fixed distance, while such arm, pressers, and levers are allowed to fall by their own weight, the roller 17 following the cam, also to a fixed distance. At the same time, the roller 28 has been riding over the cam 23^a, (or the projecting end 27 of the rod 26 has been riding against the face of the projecting piece 23), to move the rod 26 in one direction, such rod being held against the cam 23^a of the spring 29.

85 The construction and position with regard to each other of the cam 22 and the inclined ends 24^a are such that the wheel 19 only clutches the shaft 11 at a portion of each revolution, said wheel being moved longitudinally in one direction by the cam 22 engaging extension 25^a; to unclutch the wheel 19 from the member 20, and after the wheel 19 has traveled a certain distance, the projecting end 27 of the rod 26 will ride up one incline 24^a, and force back the said wheel for the clutch members 20 and 21 105 to engage until the end 27 reaches the other incline 24^a, when the cam 22 will engage the extension 25^a and force said wheel back, so that the latter does not rotate with the shaft except when the clutch members 20 and 21 are in mesh. Now should the raising of the mechanism be in accordance with the delivery of paper, the pressers 1 will press on the pile before they reach their full limit of downward movement and in consequence 110 the machine runs correctly; but should the delivery of paper not be in accordance with the movement of the mechanism, and should the pressers reach the full limit, or nearly so, of their downward movement before contacting with the pile, the rocking lever 32 will be acted upon by the arm 3. The latter depresses the roller 39 and moves up the nose 31, so that when the rod 26 has again 115 reached its highest movement, the nose 31 120

125 reaches its highest movement, the nose 31 130

engages the notch 30 of the rod 26 and holds it for a time, thus preventing the end 27 from having any action on the incline 24^a during the next portion of its revolution, 5 whereby the cam 22, having acted upon the extension 25^a, will free the wheel 19 from the clutch, so that it will run free, and there will be no further movement of the raising gear until sufficient paper is fed on to the 10 pile for the pile to offer sufficient resistance to prevent the full or nearly full lowering movement of the pressers 1.

The notch 30 and the nose 31 are undercut, so that once the arm 3 has forced the 15 said nose into said notch and the cam has moved away from supporting the roller 28 although the arm 3 may be raised, the lever 32 cannot become disengaged, in order to allow rod 26 to go forward, until the cam 20 again comes around and moves the rod 26 against the tension of the spring 29 through the medium roller 28; then lever 32 springs out and then only: that is to say, although 25 there is no weight on roller 39, yet the action of the spring 29 pulling rod 26 against the nose 31, prevents lever 32 from releasing itself until the cam moves the rod 26 against the tension of spring 29.

What I do claim as my invention and desire to secure by Letters Patent is:—

1. In a machine for piling and laying sheets of paper, the combination, with a sheet-receiving element, and side gages associated therewith; of vertically-movable 35 pressers disposed adjacent the opposite side faces of said gages and operative solely upon the edges of the pile of sheets on said element; and mechanism for raising said pressers, the pressers falling by the action of 40 gravity.

2. In a machine for piling and laying sheets of paper, the combination, with a sheet-receiving element, and side gages associated therewith; of horizontally-arranged

pressers disposed adjacent said gages and 45 operative solely upon the edges of the pile of sheets on said element; an arm from which said pressers are suspended; a vertically-movable frame carrying said arm; mechanism for lifting said arm to raise the 50 pressers, said pressers falling by the action of gravity; and mechanism for operating said frame.

3. In a machine for piling and laying sheets of paper, the combination, with a 55 sheet-receiving element and side gages associated therewith; of pressers disposed adjacent said gages and operative upon the pile of sheets on said element; means for reciprocating said pressers; a carrier with which 60 said pressers are connected; mechanism for effecting a relative vertical movement between the carrier and the sheet receiving element; and means operable by said pressers for automatically throwing said mechanism 65 out of operation when the height of the said pile falls below the normal.

4. In a machine for piling and laying sheets of paper, the combination, with a 70 sheet-receiving element and side gages associated therewith; of pressers disposed adjacent said gages and operative upon the pile of sheets on said element; a carrier with which said pressers are connected; mechanism for effecting a relative vertical move- 75 ment between the carrier and the sheet receiving element; and means operable by said pressers for automatically throwing said mechanism out of operation when the height of the said pile falls below the normal. 80

In testimony whereof I have hereunto set my hand in presence of two subscribing witnesses.

FREDERICK WILLIAM VICKERY.
